Patented Sept. 9, 1919.

FIG. 1.

FIG. 2.

FIG. 3.

FIG. 4.

FIG. 5.

14 Inventor:
JAMES C. CUNNINGHAM
By Edward E. Langdon Atty.

UNITED STATES PATENT OFFICE.

JAMES C. CUNNINGHAM, OF MOSCOW MILLS, MISSOURI, ASSIGNOR, BY DIRECT AND MESNE ASSIGNMENTS, TO SAFETY RAIL SHOE & COUPLING COMPANY, A CORPORATION OF MISSOURI.

RAIL-JOINT.

1,315,470.

Specification of Letters Patent.

Patented Sept. 9, 1919.

Application filed May 3, 1919. Serial No. 294,404.

To all whom it may concern:

Be it known that I, JAMES C. CUNNINGHAM, a citizen of the United States, and resident of Moscow Mills, county of Lincoln, 5 and State of Missouri, have invented certain new and useful Improvements in Rail-Joints, of which the following is a specification containing a full, clear, and exact description, reference being had to the accompanying 10 drawings, forming a part hereof.

This invention relates to rail joints and has for its object a rail joint wherein the spike openings are staggered so as to prevent splitting of ties when the joint is 15 secured thereto.

A further object is to provide a rail joint with recesses on alternate sides so that the bolt heads may be sunk therein and prevent the shearing off of some of the bolt heads 20 and nuts when a car is derailed.

A further object is to provide a rail joint which encircles a rail on three sides, that is the entire flange and both sides of the web, and is provided with a reinforced flange to 25 support the ball of the rail, and columns for strengthening the flange and web, the alternate columns on each side being provided with a recess for the reception of the head of the locking bolt, the portion for supporting the base being provided with staggered 30 bolt or spike openings and with staggered projections which will prevent the tie plate from creeping along the tie, and also prevent the splitting thereof.

35 In the drawings:

Figure 1 is a top plan view of my device in position.

Fig. 2 is a side elevation of the same.

Fig. 3 is a bottom plan view.

40 Fig. 4 is a vertical cross sectional view taken on the line 4—4 of Fig. 2, viewing the same in the direction of the arrow.

Fig. 5 is a similar view taken on the line 5—5 of Fig. 2.

45 In the construction of my device, I provide rails 6 and 7, their ends being placed adjacent to each other or abutting, as indicated in Figs. 1 and 2. Encircling these rails on three sides, I place my improved tie plate 8 which consists of a bottom portion 9 and two vertical portions 10. On the bottom portion 9, the bases 11 of the rails 6 and 7 rest. The bottom portion 9 is provided with 50 extending ears 12, these ears being provided with recesses 13, the ears being so staggered

as to prevent spikes driven through the openings 13 from splitting the tie, or in other words entering along the same line of grain in the tie.

The bottom portion 9 is further provided 60 with projections 14 which are also staggered and which tend to prevent the creeping side- 65 wise or spreading of the rails 6 and 7. This base is formed with overlapping flanges 15 which are substantially parallel to the base 11 of the rails 6 and 7.

The overlapping portions 15 are provided 70 with vertically extended portions 16 which fit along the web of the rail and are formed 75 integral with the portions 15. On the upper edge of the extended portions 16, I provide flanges 17 which flanges are adapted to support the under edge of the ball 18 formed on the rails 6 and 7, the portion 15, however, 80 not conforming exactly to the base of the rail, so that, when the joint is secured to the rail, the flange 17 presses against the under edge of the ball 18 and causes the edge 19 to bind tightly against the rail where the web 85 and the base meet. This will tend to stiffen or strengthen the rails at their weakest point, that is where two rails are joined, and will have a tendency to prevent sagging of the rails due to the pounding of the 90 wheels when passing over joined rails.

Along the outer edge of the flange of the rail, the opening 20 will be left. This will allow for a longitudinal creeping of the 95 rails, or in other words, for the expansion and contraction.

Along the vertical portions 16 and regularly spaced apart, I provide columns or filled in portions 21 which not only stiffen the vertical portions of the rail joint, but 100 also act as stiffeners for the web of the rail as well as to support the flanges 17 of the rail joint. These columns 21 are provided with recesses 22, the recesses being arranged 105 on alternate columns and staggered on opposite sides of the rail joint, that is, the recesses being in the left hand column of one side of the joint, would be on the right hand side in the next column, thus alternating from side to side of the rail joint.

My object in this is that in the event that a car becomes derailed, the wheels or rather the flanges of the wheels would shear only one half of the bolts securing the rails together, the method of securing these bolts 110

being fully illustrated in Figs. 1 and 5, wherein 23 represents the bolt head and 24 the nut.

That portion of the rail joint supporting 5 the ball and web of the rail is practically the width of the ball of the rail, see Figs. 4 and 5. This insures a much stronger joint than is possible with the ordinary fish plate, and at the same time allows the flange of 10 the wheel to pass freely thereover.

In the construction of my rail joint, that portion which supports the base of the rail, the vertically extending portions which support the ball thereof, and that part overlapping the top face of the base together with the supporting columns is cast of one piece of metal, forming a unitary casting, thus obviating the use of a tie plate and two fish plates.

20 Having fully described my invention, what I claim is:

1. A rail joint formed of a unitary casting and having a base for supporting the end of two adjacent rails, said base being 25 provided with spike openings and projections to secure the same to a tie and also with an extended portion to engage the edges of the base flanges of a rail, substantially horizontal portions formed integral with the 30 base and overlying the top surfaces of the base flanges of the rail and with vertically spaced apart portions adapted to fit the opposite sides of the webs of the rails each of said vertical portions being provided with a 35 flange along its top edge to conform with the under surface of the rail balls and answering as a brace therefor, and a series of vertical columns spaced apart extending from the flange to the substantially horizon-

tal portion overlying the top surfaces of the 40 base, openings or recesses formed in alternate columns on each side of the vertical portions for receiving bolt heads, said columns and flanges acting as an additional strengthening for the ball and web of the 45 rail at its joint.

2. A rail joint formed of a unitary casting and having a base for supporting the ends of two adjacent rails, said base being provided on its underneath surface with staggered projections to engage the tie and with staggered recessed ears for securing the joint by means of spikes to the tie, said base being further provided with vertical portions adapted to engage the edges of the base 55 flange of the rail and with substantially horizontal portions overlying the top surface of the base flanges, said horizontal portions provided with spaced apart vertical portions adapted to engage the opposite faces of the 60 rail webs, said portions being provided with horizontal flanges and shaped to conform with the underneath surface of the rail balls, and a series of columns extending from said flanges to the horizontal portions for strengthening said flanges and the 65 vertical portions of the rail joint which engage the rail webs, certain of said columns being provided with recesses for the reception of the heads of the bolt fastenings for 70 the rail joint.

In testimony whereof, I have signed my name to this specification, in the presence of two subscribing witnesses.

JAMES C. CUNNINGHAM.
